United States Patent Office

Des. 182,240
Patented Mar. 4, 1958

182,240

CABINET FOR AN AUTOMATIC CAMERA OR SIMILAR ARTICLE

Frederick Gordon Mackay, Tarzana, Calif., assignor to
Auto-Photo Company, Los Angeles, Calif., a corpora-
tion of California

Application August 6, 1957, Serial No. 47,250

Term of patent 14 years

(Cl. D61—1)

FIG. 1.

Des. 182,240

PAGE 2

FIG. 2.

FIG. 3.

Figure 1 is a perspective view of a cabinet for an automatic camera or similar article embodying my new design;

Figure 2 is a side elevational view of the cabinet as is indicated by arrow 2 on Figure 1; and

Figure 3 is an end elevational view as is indicated by arrow 3 on Figure 1.

I claim:

The ornamental design for a cabinet for an automatic camera or similar article, as shown.
